MANUFACTURE OF GILLED TUBES

Robert Mautsch, Brussels, Belgium, assignor to
 Manufacture Generale Metallurgique, Societe
 Anonyme, Brussels, Belgium, a Belgian com-
 pany

Application April 8, 1933, Serial No. 665,203
 In Belgium April 12, 1932

3 Claims. (Cl. 113—118)

This invention relates to the manufacture of gilled tubes of the type used, more particularly, in heat exchange apparatuses. It is well-known that the efficiency of heat-exchange apparatuses comprising gilled tubes or pipes is largely dependent upon the closeness of the contact between said tubes and the gills mounted thereupon, which may be secured in position by various means, as by expanding said tubes, or by welding, for example. It has been proposed to improve the contact between tubes and gills by combining the two said methods, or by providing the gills with collars adapted to enclose a larger area of said tubes, or again by corrugating or puckering said gills. These various methods however cannot be entirely relied upon to ensure strength in the assembled unit, the ability of the same to withstand long use, or uniform contact between gills and tubes at all points of the latter's periphery.

The object of my invention is to provide tubes having gills firmly secured thereupon, in close contact therewith, by deforming the metal of said tubes and making use of the resiliency of the metal of said gills, under conditions calculated to ensure therebetween a contact adapted to remain permanent despite oxidation and other phenomena concomitant with the ageing of assembled units.

In accordance with my invention I obtain this result by making the gills of a metal the resiliency or the hardness of which has been increased, by a mechanical or by a thermic treatment for example, to such a degree that it is substantially greater than that of the metal forming the tubes, and by causing the expansion of the tube to tension the metal of the gills sufficiently to ensure that, on contracting after release of the pressure applied for expanding the tube, each gill forms a constriction in the tube.

The metal forming the tubes may be rendered ductile, for example by an annealing treatment, in order to accentuate as much as possible the difference between the resiliency of the gills and the lesser resiliency of the tubes. When the metal of the tubes is relatively very ductile the contraction of the gills may be sufficient to cause their inner edges to embed themselves in the tube wall.

In order that the gills be imparted a great stiffness and shall not warp under the internal pressure exerted by the expanded tube, the gills may advantageously be corrugated or puckered; the corrugations formed in the gills thus produce a new effect, in addition to the known one of in-

creasing the surface available for heat exchange. To expand the tubes, I may use any suitable means, as hydraulic pressure, or a mandrel either rigid or expandible.

My improved process insures permanent and intimate contact between the tube and the gills, the latter acting as powerful springs and being permanently under elastic tension. It is particularly suitable for securing gills on thin walled tubes.

Gilled tubes according to my invention and a process for producing the same are illustrated, by way of example, in the accompanying drawing whereof:

Fig. 1 is a diagrammatic view of a gilled tube provided with swellings according to the invention;

Fig. 2 shows said tube at one stage of its production;

Fig. 3 illustrates an alternative method for forming a tube according to the invention;

Fig. 4 shows a tube provided with puckered gills.

In the various figures of the drawing, the tube generally designated by *a* is provided with a plurality of gills designated by *b*, consisting of highly resilient metal, said gills being mounted upon tube *a* which is thereupon subjected to internal pressure as, for example, by having inserted thereinto a mandrel *c* whereof the diameter is greater than the outer diameter of said tube. Upon being moved in the direction indicated by the arrow (Fig. 2), the mandrel firstly expands the tube at *a'*. When passing through the plane of the first gill, the mandrel likewise expands said gill by elastic deformation. After the mandrel has passed beyond the gill (position shown in Fig. 2) the considerable resilient energy stored therein is released, and the gill contracts to grip the tube, while a swelling *d* is formed between said gill and the next in succession. Upon having been thus distorted, the gill possesses sufficient stored resilient energy to cause it to exert upon the tube a degree of pressure which is all the greater that the expansion of the latter has been more marked.

As shown in Fig. 1, the finished tube displays a succession of swellings *d*, separated from each other by constrictions gripped by the gills.

Fig. 3 illustrates the use of an expandible mandrel *e* consisting, for example, of a resilient head and of a wedge-shaped member *f*, adapted to be moved intermittently and alternately, so that the head member *e* may be expanded whenever situated between two gills and thereby expand the

tube at that spot. In this alternative, the de-forming effect upon the gills may be less than when a rigid mandrel is used.

An expandible mandrel may also be applied 5 after the rigid mandrel, in order to deepen the corrugations made in the tube by the latter.

It is generally of advantage that the gills be formed of a highly resilient metal, in order that the edges of their holes surrounding the tube 10 should grip the latter firmly and exert permanent pressure thereupon. On the other hand, the metal of the tube must have a degree of ductility sufficient to cause swellings to be formed therein by the combined action of the mandrel and the 15 gills. Should the metal of said tube be very much more ductile than that of the gills, the latter will embed themselves in the constrictions between the swellings and thus further enhance the closeness of the contact.

20 It is likewise important that the gills be sufficiently stiff to remain unwarped by the expansion stresses set up by the passage of the mandrel. To this end, the use of corrugated or puckered fins such as illustrated in Fig. 4 is of special 25 advantage, the gill being stiffened by numerous small folds or puckers formed therein, whereby stresses set up by the expansion of the tube are distributed uniformly throughout said gill without causing the same to warp or distort beyond 30 the recuperative capacity of the metal of which it consists.

The process hereinbefore disclosed may of course be applied to tubes having a non circular cross-section or to an assemblage of fins traversed 35 by several tubes, and the constructional embodiment of the invention may be modified in various ways without departure from its scope as defined in the appended claims.

I claim:

1. A process of manufacturing gilled tubes, comprising making gills of a metal substantially more resilient than the metal of the tubes, threading the gills on a tube, passing through 5 said tube a rigid mandrel of such size with respect to the diameters of the tube and of the holes in the gills, that the tube is permanently deformed while the gills are only elastically deformed, thus causing the gills by their subsequent 10 contraction to form constrictions in the tube and exert a predetermined elastic pressure thereon.

2. A process of manufacturing gilled tubes, comprising forming gills of sheet metal, hardening the metal of said gills, then threading said 15 hardened gills on a tube of relatively ductile metal, the holes in the gills being just large enough to accommodate said tube, passing through said tube a rigid mandrel of such size with respect to the diameter of the tube that 20 the tube is permanently expanded while the gills are elastically deformed, along the whole periphery of their holes, causing the gills to contract, constrict the tube and exert thereon a predetermined elastic pressure.

3. The process of manufacturing gilled tubes comprising treating the gills to make the metal thereof substantially more resilient than the metal of the tube, then placing a plurality of 30 said gills upon a tube, then subjecting the tube to internal pressure to expand the tube and elastically deform said gills and then releasing said pressure whereby said gills are permitted to retract and form constrictions in said tube. 35

ROBERT MAUTSCH.
